CLAIM

The ornamental design for ski boot tote, as shown and described.

DESCRIPTION

FIG. 1 is a perspective view of a ski boot tote showing my new design;

FIG. 2 is a front elevational view, the rear elevational view being a mirror image thereof;

FIG. 3 is a top plan view thereof;

FIG. 4 is a left side elevational view, the right side being a mirror image thereof;

FIG. 5 is a bottom plan view thereof;

FIG. 6 is a perspective view of the tote in use.

The broken line showing of a hand and ski boots in FIG. 6 is for illustrative purposes only and forms no part of the claimed design.
